G. L. LAWRENCE

OVERSHOE

Filed June 14, 1927

UNITED STATES PATENT OFFICE.

GEORGE L. LAWRENCE, OF MELROSE, MASSACHUSETTS.

OVERSHOE.

Application filed June 14, 1927. Serial No. 198,709.

My present invention relates to overshoes, and is directed to a novel construction of overshoe as a new article of manufacture.

The usual prior method of manufacturing overshoes has been to last up a lining to an insole and filler, then apply a toe strip, counter, heel piece, and the like, then to provide a quarter, usually provided with a pocket, and a vamp, and to last this over the lining with its component parts already assembled, and then to apply the foxing and an outsole. In some instances this process has been varied by assembling some of the cut-out parts beforehand, viz, assembling them flat, but the structure of the completed overshoe has been invariably the same.

An important object of my present invention is the provision of an overshoe which will be much lighter in weight, which will be much neater because of the absence of seams inside of the overshoe, and which will present an extremely material saving in cost, as well as resulting in a more comfortable and better fitting overshoe. To this end, I preferably provide a laminated upper structure, viz, a laminated quarter and a laminated vamp. Thus the upper of my novel overshoe comprises only two pieces, viz, the quarter and the vamp. These two pieces or parts of the upper may be formed in several different manners, viz, both the quarter and the vamp may be formed of the same material inside and outside, or the quarter may be formed of a different material on the interior lamination, so that when a cuff is folded over, as in some forms of overshoes, a material different from that on the outside of the quarter will be presented to the eye. Or the interior lamination of the quarter portion may consist of two different materials, viz, a cheap material to take the place of the lining, and an expensive and attractive material to form the cuff portion. The vamp laminations may likewise be varied, and the interior lamination of the vamp may consist of a cheaper fabric than that of the outside lamination. These two upper portions, quarter and vamp, are then assembled with an insole and filler, on a last. A second filler is then attached. A toe strip is then applied, and a counter is also applied over the heel, both the toe strip and counter being applied over both layers of the laminated upper portions. To the thus far assembled overshoe is then applied the foxing, after which the usual outsole is applied and rolled. This results in a very simple and

inexpensive process of overshoe manufacture, and consequently effects a material saving in the cost of manufacture. The counter or heel piece may be a combination counter or not, as desired, or it is possible to manufacture my present novel overshoe without a counter. The toe strip may or may not be made and reinforced with an underlying strip of fabric. As to the strap, forming an essential part of this overshoe, this may or may not be made part of the quarter, this being optional in the manufacture.

My present invention is not limited to the cuff gaiter type of overshoe, but will apply equally well to regular overshoes, viz, the one-buckle type of overshoe, where the outside upper material may be laminated with fleece or other lining, and a buckle utilized in place of the strap. My construction will also apply equally well to high gaiters or overshoes, as well as to the type of rubbers known as "Alaskas."

Further features of the invention, details of construction, combination of parts, and advantages, will be hereinafter more fully pointed out and claimed.

Referring to the drawings, illustrating a preferred embodiment of the present invention,

Fig. 1 is a side elevation of a completed overshoe constructed according to my present invention;

Fig. 2 is a cross sectional view on the line 2—2 of Fig. 1;

Fig. 3 is a longitudinal sectional view on the line 3—3 of Fig. 2;

Fig. 4 is a cross sectional view on the line 4—4 of Fig. 1;

Fig. 5 is a fragmentary cross sectional detail illustrating the first step in the method of manufacture;

Fig. 6 is a cross sectional view illustrating the second step;

Fig. 7 is a fragmentary cross sectional detail illustrating the third step;

Fig. 8 is a fragmentary cross sectional detail illustrating the final and complete step of the process before removing the overshoe from the last; and

Fig. 9 is a side elevation of an "Alaska" constructed according to my present invention.

As shown in the drawings, on a last 1 is mounted an insole 2, with which is assembled, preferably beforehand, a filler 2^a, and to this insole, on the last, are applied and lasted the upper materials 3. These upper materials

comprise but two parts, viz, a vamp 4 and quarter 5. These vamp and quarter sections are comprised of laminated material, consisting of two laminations 6 and 7. These vamp 5 and quarter portions may be constructed of different materials, viz, the quarter 5 may have an outside lamination of attractive material, and an inside lamination, for the lining portion, of a cheaper material, the top of 10 the inside lamination, which is adapted to be turned over to form the cuff 8, in the type of overshoе illustrated herein, being of either the same material as the outer lamination, or of a different material, either in quality or 15 color, so that the cuff will present a different appearance than the outside material of the quarter. The vamp 4 may be formed or constructed with the same material for the outside lamination as that of the outside of the 20 quarter, and with an inexpensive or different material for the lining of said vamp. All of these changes or designs are clearly within the scope of the present invention, so long as I adhere to the principle of applying to the 25 last an already laminated upper. The upper materials are preferably laminated in sheets, and then cut out. Thus each upper piece, viz, quarter and vamp, will have a lining formed integral therewith and of identically 30 the same shape as the quarter or vamp with which it is formed. These upper materials, as clearly shown in Fig. 5, are lasted onto the insole 2 and filler 2^a as shown at 9. A second filler, of cloth, fabric, or rubber, 2^b, is then 35 applied. Over the upper materials and insole is then applied a counter, illustrated generally at 10, this counter extending down over the bottom of the filler 2^b, as illustrated at 11. The shoe upper portions, viz, quarter 40 and vamp, are united preferably by an over-casting stitch as shown at 12 in Fig. 1, the cuff portion being stitched in the same operation, as at 13, to insure uniting of the laminations at the edges, to prevent fraying thereof, 45 and also to add to the neat appearance of the overshoе. This stitching is preferably performed prior to lasting. The counter 10 may consist of a combination counter and heel 50 piece, or this counter may be eliminated, if desired. Over the thus assembled portions, at the heel, is then applied the foxing 14, turned under at the bottom over the counter, as at 15. The toe boxing 16 is applied either before or after the heel boxing, and the over- 55 shoe is now in condition for application of the outsole. The outsole 17 is then applied, and preferably rolled, to finish the overshoе, and produce the corrugations illustrated at 18, as is usual.

60 At the heel portion of the overshoе, as illustrated in Fig. 2, the quarter is slit up at the bottom for a short distance, to the point shown at 19, and lapped over as shown at 20, and cemented, or may be stitched or piped.

65 A strap 21 provided with a snap or buckle

22 is also provided, across the front of the overshoе, the vamp being folded or lapped to form a pocket 23, adjustable to the size of the leg of the wearer. It will thus be appreciated that the pocket 23 is formed without the 70 utilization of any separate pocket strip or piece on the interior of the shoe, the upper materials, as above stated, consisting of only two pieces, viz, quarter and vamp, the linings of both the quarter and vamp being made 75 as an integral part thereof before assembly. Thus my novel overshoе has a smooth, unbroken interior, both of quarter and vamp, resulting in a much neater, more comfortable, less bulky and more attractive overshoе. 80 It will be appreciated that the overshoе may be made without the cuff 8, and may be utilized as a buckle overshoе, either with one or more buckles, and of varying height. Also, the strap 21 may be formed or cut as an 85 integral part of the quarter, if desired, or may be separately stitched or adhered thereto. My present invention is equally applicable to overshoes or rubbers of the type where- 90 in the upper materials consist of a single up- 95 per, instead of quarter and vamp. The well known "Alaska" is an example of this type of shoe protector, and in Fig. 9 I have illus- 100 trated, on a reduced scale, an Alaska con- 105 structed according to my present invention, 105 wherein the upper 25 is formed of a single laminated structure. This is preferably 110 formed in the same manner as described for the overshoes, viz, the laminated upper ma- 115 terials are first assembled and laminated in sheet formation. Apart from this one piece 120 upper construction, the method of construct- 125 ing the Alaska shown in Fig. 9 is similar to the method described for the overshoе, this Alaska having a foxing 26, heel piece 27, 125 counter 28 and outsole 29. It will be instant- 130 ly apparent that my present novel method of construction can be carried out equally as thoroughly in the manufacture of a rub- 135 ber or overshoе having a single upper, as can be practiced in overshoes or rubbers hav- 140 ing upper materials consisting of a quarter 145 and vamp.

While I have necessarily described my present invention somewhat in detail, it will 150 be appreciated that I may vary the shape, 155 design, and arrangement of parts, within reasonably wide limits, without departing 160 from the spirit of the invention.

My invention is further described and de- 165 fined in the form of claims as follows:

1. An overshoе of the kind described, comprising upper materials consisting of a laminated quarter and a laminated vamp lasted 170 over onto an insole, a counter overlying said laminated upper materials and extending un- 175 der said insole, a heel foxing over said coun- 180 ter, a toe foxing, and an outsole.
2. An overshoе of the kind described, comprising upper materials consisting of a lami- 185

nated quarter and a laminated vamp united by stitching and lasted over onto an insole, a counter overlying said laminated upper materials and extending under said insole, 5 a heel foxing over said counter, a toe foxing, and an outsole.

3. In an overshoe of the kind described, a quarter and quarter lining both of the same shape and size, said quarter and lining being extended beyond the normal height of 10 said overshoe to form an integral cuff, and a vamp and vamp lining both of the same shape and size, said vamp and lining being folded to form pockets without the addition 15 of separate pocket forming portions, said vamp and vamp lining and quarter and quarter lining being united by stitching.

4. In an overshoe of the kind described, a

quarter and quarter lining both of the same shape and size, said quarter and lining being extended beyond the normal height of 20 said overshoe to form an integral cuff, and a vamp and vamp lining both of the same shape and size, said vamp and lining being folded to form pockets without the addition 25 of separate pocket forming portions, said vamp and vamp lining and quarter and quarter lining being united by stitching, said stitching extending beyond the union of the vamp and quarter and completely around and 30 uniting the edges of that portion of the quarter and quarter lining which constitutes the cuff.

In testimony whereof, I have signed my name to this specification.

GEORGE L. LAWRENCE.
